UNITED STATES PATENT OFFICE

MAXWELL H. SPREEN, OF DETROIT, MICHIGAN, ASSIGNOR TO KELVINATOR CORPORATION, OF DETROIT, MICHIGAN, A CORPORATION OF MICHIGAN

CONTROL MECHANISM FOR MECHANICAL REFRIGERATING APPARATUS

Application filed October 7, 1927. Serial No. 224,544.

My invention relates to mechanical refrigerating systems and it has particular relation to a novel method of controlling the operation thereof.

Heretofore, it has been customary, in the mechanical refrigerating art, to control the operation of the motor which drives the compressor by means of an electrical switch operated by a thermostat disposed within the refrigerator. This type of control is satisfactory under ordinary circumstances but under certain circumstances, such for example, as a refrigerator disposed in an unheated room during the winter months, the temperature of the refrigerator is sufficiently low to prevent the thermostat from starting the compressor motor but is, nevertheless, too high to freeze water. This condition is objectionable because it is then impossible to freeze the ice cubes which are desirable for table use.

By my invention I have eliminated this objection and have provided means adapted to operate in conjunction with the thermostat to cause it to operate to both energize and de-energize the motor under the circumstances indicated.

One object of my invention consists in providing novel means whereby the functioning of a thermostat in a mechanical refrigerating system at regular intervals is insured.

Another object of my invention is to provide means for producing abnormal temperature conditions adjacent the thermostat without substantially affecting the temperature of the refrigerator as a whole.

A further object of my invention consists in providing means for causing the thermostat to actuate the motor at intervals irrespective of the temperature of the ambient medium while permitting the thermostat to regulate the length of the period of such operation.

A further object of my invention is to provide means for insuring that the temperature of the refrigerator is reduced to the lower limit of the range of the thermostat at intervals.

For a better understanding of my inven-

tion reference may now be had to the accompanying drawing of which:

Fig. 1 is a vertical cross-sectional view of a refrigerator having a mechanical refrigerating system embodying my invention installed therein, and

Fig. 2 is an enlarged fragmentary partially cross-sectional view of the motor control equipment illustrated in Fig. 1.

My invention is herein shown as applied to a mechanical refrigerating unit consisting of refrigerant expansion apparatus 11 mounted in a refrigerating compartment 12 of a domestic refrigerator cabinet 13, in which is disposed a brine tank 14. The tank 14 is provided with a recess 15 for the reception of trays 16 for the formation of congealed fluid under the action of the refrigerant expansion apparatus 11, and encloses a refrigerant expansion coil 17 disposed within the brine tank 14 and encircling the recess 15. An expansion valve 18 is connected to an inlet end 19 of the expansion coil 17 and is secured to the top of the tank 14. A coiled tube 20 is connected to an outlet end 21 of the expansion coil 17, and is disposed adjacent to the top of the tank 14 in the path of the warm air current from the storage compartment of the refrigerator and partially encloses and serves as a support for a thermostatic unit 22, provided with a bellows 23, disposed within the coiled tube 20.

Refrigerant compressing mechanism 23, located at any suitable point, comprises a compressor 24 having an inlet port 25, connected, by means of a duct or tube 26, to an outlet end 27 of the coiled tube 20. A refrigerant condenser 28, having one end 29 thereof connected to an outlet port 30 of the compressor 24 has its other end 31 connected, by means of a duct or tube 32, to the expansion valve 18. An electric motor 33 operates the compressor 24 by means of a suitable belt 34.

The motor control mechanism comprises a switch blade 35 pivotally mounted upon an insulating switch base 36 by means of a stud 37, and is operated by the bellows 23 of the thermostatic unit 22 between a lower position contacting with a contact clip 38 mounted on the base 36 by means of a stud 39, and an

upper position contacting with an upper clip 40 mounted on the base 36 by means of a stud 41. The blade 35 actuated by means of a spring 35^a mounted upon a guide rod 35^b, 5 which in turn is pivotally mounted upon a vertically slidable member 23^a connected to the bellows 23. As the pivotal connection between the guide rod 35^b and the member 23^a is moved by the bellows 23 to a point above 10 the stud 37 the spring 35^a forces the blade out of contact with the contact clip 40 and into contact with the contact clip 38. In like manner, when the member 23^a is moved downwardly by the bellows 23 the spring 35^a moves 15 the arm 35 out of contact with the clip 38 and into contact with the clip 40.

By means of the stud 39 the contact clip 38 is electrically connected to a conductor 45, the stud 37 connects the blade 35 to a conductor 43, and the stud 41 connects the contact clip 40 to a conductor 46. Secured to the thermostat adjacent to the bellows 23 is an electrical heating unit 42, which is enclosed within a protective casing 42^a and to 20 one end of which the conductor 46 is connected through a manually operable contact switch 55. The opposite end of the heating unit is connected to a conductor 47. The three conductors 43, 45 and 47 extend through an 25 armored conduit to a point adjacent the motor at which point the conductor 43 is connected to one side of an electrical circuit by means of a conductor 44, and the conductor 47 is connected to the opposite side of the 30 electrical circuit by means of a conductor 51. The conductor 45 is connected to one terminal of the motor 33 and the opposite terminal of the motor is connected to the conductor 47, as indicated at 48 by means of a conductor 49.

Having described the construction of an apparatus embodying my invention, its operation is as follows: Assuming that the refrigerator has reached the uppermost limit of the range of the thermostat, expansion of the bellows 23 raises the member 23^a causing the blade 35 to move into engagement with the contact member 38. When the switch blade 35 engages the contact 38 a circuit is completed from conductor 44, through conductor 43, stud 37, switch blade 35, contact clip 38, stud 39, conductor 45, the motor 33, and conductor 49 to conductor 51, thus energizing the motor and operating the compressor 24. When operation of the compressor 24 has, through the agency of the expansion coil 17 reduced the temperature of the refrigerator to a sufficient degree, the contraction of the bellows 23 draws the member 23^a downwardly, thus causing the switch 55 blade 35 to break contact with the contact clip 38 and engage the contact clip 40. A circuit is thus completed from conductor 44, through conductor 43, stud 37, switch blade 35, contact clip 40, stud 41, conductor 46, 60 switch 55, heating coil 42 and conductor 47 65

to conductor 51, thus de-energizing the motor and causing a current to flow through the heating coil 42. The heating coil 42, being disposed adjacent the bellows 23, transmits the major portion of its heat thereto and raises its temperature without materially raising the temperature of the refrigerator as a whole. 70

The result of this arrangement of parts and circuits is that, irrespective of the temperature of the room in which the refrigerator is placed, the heating coil 42 causes intermittent energization of the motor, thus insuring that the refrigerator temperature will reach the lower limit of the range of the thermostat, so that ice will be formed in the freezing tray under any and all conditions. 75

During the warm months of the year the heating action of the coil 42 is, of course, not required. In order that unnecessary heat may not be admitted to the refrigerator under these conditions the manually operable switch 55 is manipulated in such manner that the circuit through the conductor 46 to the heating coil 42 is broken, thus permitting 80 the operation of the refrigerating apparatus in the usual manner. 85

Although I have illustrated but one form of my invention and have described in detail but a single application thereof, it will 90 be apparent to those skilled in the art, that various modifications and changes may be made therein without departing from the spirit of my invention or from the scope of the appended claims. 95

What I claim is:

1. In a mechanically cooled refrigerator, a thermostat responsive to the temperature of the refrigerator and operating to automatically regulate the temperature within 105 said refrigerator, and means operatively associated with the cooling mechanism for changing the temperature of the medium surrounding the thermostat.

2. In a mechanically cooled refrigerator, a 110 thermostat responsive to the temperature of the refrigerator and operating to automatically regulate the temperature within said refrigerator, and heating means disposed in heat transferring relation with said thermostat. 115

3. In a mechanically cooled refrigerator, a thermostat responsive to the temperature of the refrigerator and operating to automatically regulate the temperature within said refrigerator, and automatically operated heating means disposed adjacent said thermostat. 120

4. In a mechanically cooled refrigerator, a 125 thermostat responsive to the temperature of the refrigerator and operating to automatically regulate the temperature within said refrigerator, and automatically operated heating means disposed adjacent said thermostat. 130

mostat, and means for rendering said heating means ineffective.

5. In combination in a refrigerator, a mechanical refrigerating system comprising a compressor, an electric motor for driving said compressor and a cooling unit, said unit being disposed within the refrigerator, a thermostat disposed within the refrigerator and adapted to control the operation of the 10 motor in accordance with temperature conditions within the refrigerator, and heating means disposed within the refrigerator immediately adjacent the thermostat and adapted to the temperature of the refrigerator 15 immediately adjacent the thermostat.

6. In combination in a refrigerator, a mechanical refrigerating system comprising a compressor, an electric motor for driving said compressor and a cooling unit, said unit 20 being disposed within the refrigerator, a thermostat disposed within the refrigerator and adapted to control the operation of the motor in accordance with temperature conditions within the refrigerator, and heating 25 means disposed within the refrigerator adjacent the thermostat.

7. In combination in a refrigerator, a mechanical refrigerating system comprising a compressor, an electric motor for driving said 30 compressor and a cooling unit, said unit being disposed within the refrigerator, a thermostat disposed within the refrigerator and adapted to control the operation of the motor in accordance with temperature conditions within the refrigerator and heating 35 means disposed within the refrigerator adjacent the thermostat and means for automatically energizing said heating means when the motor is de-energized.

40 8. In combination in a refrigerator, a mechanical refrigerating system comprising a compressor, an electric motor for driving said compressor and a cooling unit, said unit being disposed within the refrigerator, a 45 thermostat disposed within the refrigerator, and a heating element disposed within the refrigerator adjacent the thermostat, an electrical switch operably connected to said thermostat, said switch being adapted to con-

trol the energization of the motor and the heating coil.

9. In combination in a refrigerator, a mechanical refrigerating system comprising a compressor, an electric motor for driving 70 said compressor and a cooling unit, said unit being disposed within the refrigerator, a thermostat disposed within the refrigerator, and a heating element disposed within the refrigerator adjacent the thermostat, an electrical switch operably connected to said thermostat, and electrically connected to both the heating coil and the motor, and being adapted to automatically deenergize the motor and energize the heating coil when the thermostat reaches a predetermined low degree of temperature and to de-energize the heating coil and energize the motor when the thermostat reaches a predetermined high degree of temperature. 80

10. In combination in a refrigerator, a mechanical refrigerating system comprising a compressor, an electric motor for driving said compressor and a cooling unit, said unit 90 being disposed within the refrigerator, a thermostat disposed within the refrigerator, and a heating element disposed within the refrigerator adjacent the thermostat, an electrical switch operably connected to said thermostat, and electrically connected to both the heating coil and the motor, and being adapted to automatically de-energize the motor and energize the heating coil when the thermostat reaches a predetermined low degree of temperature and to de-energize the heating coil 95 and energize the motor when the thermostat reaches a predetermined high degree of temperature, and manually actuated means for rendering said heating coil inoperative. 100

11. In a mechanically cooled refrigerator, a cooling apparatus comprising a closed refrigerant fluid circulating system, a condensing unit, a motor for operating the condensing unit, a heating coil for increasing the temperature of the refrigerant fluid, and means for electrically energizing the motor and the heating coil alternately. 105 110
